SELF-OPENING DIE HEAD

Royce M. Strickland, New Haven, Conn., assignor, by mesne assignments, to Greenfield Tap and Die Corporation, Greenfield, Mass., a corporation of Massachusetts

Application April 20, 1948, Serial No. 22,052

6 Claims. (Cl. 10—95)

1

The present invention relates to improvements in self-opening die-heads and relates more particularly to self-opening die-heads which are suitable for the cutting of tapered threads, though also available for the cutting of straight threads.

One of the main objects of the present invention is to provide a superior self-opening die-head characterized by the compact arrangement of its elements and its suitability for being rotated at high speeds without causing centrifugal force to interfere with its proper operation.

Another object of the present invention is to provide a superior self-opening die-head capable of cutting tapered threads and characterized by reliability of operation and resistance to the disarrangement of its parts.

Another object of the present invention is to provide a superior self-opening die-head having a construction and arrangement of parts whereby it is substantially free of cramping or binding of its parts under stress.

Still another object of the present invention is to provide a self-opening die-head of the general character referred to which is provided with a plurality of thread-cutting chasers and is capable of accurately cutting threads which progressively decrease in diameter as the cutting operation progresses, and characterized by the surety with which each and every one of its chasers will perform its share of the threading task.

Still further object of the present invention is to provide a superior self-opening die-head capable of cutting tapered threads in an accurate and reliable manner and provided with superior means whereby its plurality of thread-cutting chasers may be progressively and accurately moved radially with respect to the work being threaded by either the work itself, or by external means.

Other objects will be apparent to those skilled in the art from the following, considered in conjunction with the accompanying drawings.

In the accompanying drawings, in which certain modes of carrying out the present invention are shown for illustrative purposes:

Fig. 1 is a view in front elevation of one form which a self-opening die-head embodying the present invention may assume with the chasers shown in position for the start of the cutting of a taper thread;

Fig. 2 is a view thereof in side elevation;

Fig. 3 is a central longitudinal sectional view taken on the line 3—3 of Fig. 1, but on a larger scale;

2

Fig. 4 is a transverse sectional view taken on the line 4—4 of Fig. 3;

Fig. 5 is a similar view, but taken on the line 5—5 of Fig. 3;

Fig. 6 is a broken longitudinal sectional view taken on the line 6—6 of Fig. 5;

Fig. 7 is a similar view, but taken on the line 7—7 of Fig. 5;

Fig. 8 is a broken longitudinal sectional view taken on the line 8—8 of Fig. 5;

Fig. 9 is a perspective view of the control-plate detached;

Fig. 10 is a similar view of the control-sleeve detached;

Fig. 11 is a perspective view of the control-plate, control-sleeve and actuating-bar shown in the positions which they assume at the start of the thread-cutting operation;

Fig. 12 is a view similar to Fig. 11, but showing the parts in the positions which they assume after the completion of the threading operation and after the movement of the thread-cutting chasers into their retired or clearance positions;

Fig. 13 is a central longitudinal sectional view similar to Fig. 3, but showing the parts in the positions which they assume upon the completion of the thread-cutting operation and just prior to the movement of the parts into position to permit the retirement of the thread-cutting chasers;

Fig. 14 is a perspective view similar to Fig. 11, but showing a slight modification of the elements in order to secure the production of a straight thread; and

Fig. 15 is a view similar to Figs. 11 and 14, but showing a still further modification of the elements in order to provide for the production of tapered threads which progressively increase in diameters as the threading operation progresses.

40 The structure of Figs. 1 to 13 inclusive.

The particular self-opening die-head chosen for illustration in Figs. 1 to 13 inclusive for purposes of making clear a preferred embodiment of the present invention, is so organized as to cut tapering threads which progressively decrease in diameter as the threading operation progresses in contradistinction to an organization which progressively increases the diameters of the threads as the cutting operation progresses.

The particular self-opening die-head referred to includes a body-member generally designated by the reference character 20 which, in turn, includes at its front a relatively-large-diameter head-portion 21 and a rearwardly-extend-

ing integral shank 22. The said body-member is formed with an axially-extending cylindrical chamber 23 which opens through the forward face of the head-portion 21 and which extends continuously rearwardly into the shank 22, as is especially well shown in Figs. 3 and 13.

The head-portion 21 of the body-member 20 is formed in its forward face with four (more or less) equidistant radial guide-slots 24, each of which intersects at its inner end of the chamber 23 and at its outer end intersects the outer periphery of the head-portion 21.

Mounted with capacity for reciprocation in an axial direction in each of the guide-slots 24, is one of four similar chasers 25 which are retained in place in the said guide-slots by means of four segmental retaining-plates 26 secured to the front face of the head-portion 21.

Each chaser 25 is provided with a rearwardly-extending pin 27, the inner face of which is engaged by the outer end of a cup-shaped plunger 28. Each cup-shaped plunger 28 is mounted for reciprocating movement in a substantially-radial bore 29 formed in the head-portion 21. Each plunger 28 is yieldingly urged radially outwardly by means of a helical spring 30 fitting within the adjacent hollow plunger and thrusting at its inner end against the bottom wall of the particular bore 29 in which the said spring is mounted, all as is especially well indicated in Figs. 3 and 13.

Each of the chasers 25 before referred to has a sloping cam-surface 31 at its outer end which is adapted to be engaged by one of four similarly sloping cam-surfaces 32 formed upon the inner forward corner of a cup-shaped chaser-operating sleeve generally designated by the reference character 33.

Within its forward portion, the chaser-operating sleeve 33 is formed with a relatively-large-dia-metered bearing-surface 34 and in its rear portion with a relatively-small-dia-metered bearing-surface 35. The bearing-surface 34 reciprocates with a smooth sliding fit upon the outer periphery of the head-portion 21 of the body-member 20, while the bearing-surface 35 in the chaser-operating sleeve is adapted to reciprocate with a smooth sliding fit upon the outer periphery of a control-sleeve generally designated by the reference character 36, and which will later herein be described in more detail.

The chaser-operating sleeve 33 is limited to reciprocating movement lengthwise with respect to the body-member 20 by being provided in the interior of its forward portion with a keyway 37 receiving with a sliding fit the outer end of a key 38 seated in the outer periphery of the head-portion 21 of the body-member 20, all as is indicated in Fig. 7.

Mounted, in turn, upon the outer peripheries of the chaser-operating sleeve 33 with capacity for reciprocation in an axial direction with respect thereto, is an actuating-sleeve generally designated by the reference character 39. Within its forward portion, the said actuating-sleeve is formed with a relatively-large-dia-metered bearing-portion 40 and within its rear portion with a relatively-small-dia-metered bearing-portion 41 respectively bearing upon the large-dia-metered outer surface of the forward portion of the chaser-operating sleeve 33 and the small-dia-metered rear portion of the outer periphery thereof. Adjacent its rear end, the actuating-sleeve 39 is formed in its outer periphery with an

annular groove 42 for purposes as will herein-after appear.

For the purpose of limiting the movement of the actuating-sleeve 39 to an axial direction with respect to the chaser-operating sleeve 33 upon which it is mounted, the interior of the rear portion of the said actuating-sleeve is formed with a longitudinal keyway 43 receiving with a free sliding fit a key 44 seated in the outer periphery of the adjacent portion of the chaser-operating sleeve, as is shown in Fig. 7.

Rigidly secured within the chaser-operating sleeve 33 against the forwardly-facing wall 45 therein, forming the junction between the bearing-surfaces 34 and 35, is a ring-like control-plate generally designated by the reference character 46. The said control-plate is rigidly held in place by a suitable number of screws 47 one of which is shown in Fig. 6.

Thrusting rearwardly against the forward face of the control-plate 46 are two cup-shaped plungers 48-48, both of which appear in transverse section in Fig. 5, from which it will be noted that the said plungers are located diametrically opposite each other. One of the plungers 48 appears in side elevation in Fig. 6 wherein it is shown (both plungers being identical) as mounted for reciprocation in a direction lengthwise of the structure in the head-portion 21 of the body-member 20. The said plunger receives the rear end of a helical spring 49 which presses at its forward end against the rear face of the adjacent one of the retaining-plates 26, to thereby yieldingly urge its complemental plunger 48 rearwardly. The rearward thrust exerted by the plungers 48-48 serves to yieldingly rearwardly urge the unit comprising the chaser-operating sleeve 33 and the control-plate 46 secured thereto.

For the purpose of yieldingly urging the control-sleeve 36 rearwardly with respect to the body-member 20 upon which it is mounted, there are provided two plungers 50-50 respectively located diametrically opposite each other, as is indicated in Fig. 5. Each of the said plungers 50 corresponds to the other and each thereof, like the showing of Fig. 8, is mounted for reciprocation in a pocket 51 extending lengthwise in the control-sleeve 36 and opening through the forward face thereof. Each of the said plungers is urged forwardly by a helical spring such as the spring 52 indicated in Fig. 8. The spring-pressed plungers 50 just described, serve to normally yieldingly maintain the rear face of the control-sleeve 36 seated against a ball-bearing assembly 53, as is indicated in Figs. 3, 6, 7, 8 and 13.

The ball-bearing assembly 53 above referred to, rides against the forward face of an adjusting-sleeve 54 which is threadedly connected to the outer periphery of the shank 22 of the body-member 20 immediately to the rear of the control-sleeve 36. The turning of the adjusting-sleeve 54 serves to change the normal axial position of the control-sleeve 36 as may be required for adjusting the diameters of the threads to be cut by the chasers 25. Mounted in the outer periphery of the adjusting-sleeve 54 is an inwardly-retirable stop-member 55 which normally serves to stop the rearward movement of the chaser-operating sleeve 33 when the same is released to the action of the spring-pressed plungers 48, in a manner as will hereinafter appear.

Mounted within the chamber 23 in the body-member 20, is an actuating-slide 56 which is adapted to reciprocate in the said chamber, in

a manner as will hereinafter appear. The said actuating-slide is formed with a central-longitudinal bore 57 and with a diametrical bore 58, both of which bores intersect each other, as is clearly shown in Figs. 3, 4 and 13.

Threaded into the longitudinal bore 57 in the actuating-slide 56, is an adjustable abutment-member 59 which is adapted to have its forward end engaged with the outer end of a piece of work being threaded, in a manner as will hereinafter appear. The periphery of the rear portion of the abutment-member 59, is provided with a plurality of longitudinal detent-grooves 60, which are adapted to be sequentially engaged by a lock-screw 61 and by a detent-ball 62. The said lock-screw 61 is threaded into one end of a rod-like actuating-bar 63 which extends through the diametrical bore 58 in the actuating-sleeve 56. The detent-ball 62, above referred to, is mounted in the end of the actuating-bar 63, opposite the lock-screw 61, and is yieldingly pressed into engagement with one of the detent-grooves 60 of the abutment-member 59, by means of a helical spring 64, as is shown especially well in Fig. 4.

The actuating-slide 56 and the parts carried thereby, including the elements 59 and 63, are yieldingly urged forwardly by means of a helical spring 65, as is shown in Figs. 3 and 13. The central portion of the actuating-bar 63 is provided with a diametrical passage 63a for the reception of the abutment-member 59.

From the foregoing and by reference to the drawings, it will be observed that the actuating-bar 63 extends diametrically with respect to the actuating-slide 56 and projects from the respective opposite sides thereof, as is especially well shown in Figs. 3, 4 and 13. The adjustable-abutment-member 59, the detent-grooves 60 of which are engaged by the locking-screw 61 and detent-ball 62, extends diametrically through the central portion of the actuating-bar 63.

The shank 22 of the body-member 20 is formed at diametrically-opposite points with longitudinal clearance-slots 66-66 through both of which the actuating-bar 63 extends with freedom for sliding movement therein in a direction lengthwise of the body-member 20.

The control-sleeve 36 is, in turn, formed at diametrically-opposite points with two actuating-slots 67-67 through which the actuating-bar 63 extends with freedom for movement lengthwise in the said actuating-slots. The actuating-slots 67-67 just referred to instead of extending in parallelism with the axis of the body-member 22, are inclined in a helical path, as is especially well shown in Figs. 10, 11 and 12.

The rear portion of the chaser-operating sleeve 33 is formed at diametrically-opposite points with clearance-slots 68-68 through which extends the actuating-bar 63.

The respective opposite ends of the actuating-bar 63, above described project into clearance-grooves 69-69 formed within the interior of the rear portion of the actuating-sleeve 39. The said clearance-grooves extend in a direction paralleling the axis of the said actuating-sleeve.

Leading radially from the outer surface of the actuating-sleeve 39 respectively into intersecting relationship with respect to the clearance-grooves 69-69, are threaded passages 70-70 respectively, threadedly receiving plugs 71-71, which latter serve to exclude dirt, chips and other foreign matter from the interior of the die-head. One

of the said plugs 71 may be removed to afford access to the lock-screw 61.

The ring-like control-plate 46 is provided with four (more or less) inwardly-extending control-fingers 72 equidistantly spaced from each other in a circumferential direction and each having its rear face sloped to provide a rearwardly-facing control-surface 73. The control-surfaces 73 substantially correspond in inclination to the inclined, forwardly-facing, control-surfaces 74 formed upon the control-sleeve 36 slightly to the rear of the extreme forward end of the said control-sleeve.

Circumferentially adjacent the forward terminus of each of its control-surfaces 74, the control-sleeve 36 is formed with one of four similar forwardly-opening clearance-notches 75 which are respectively adapted to receive one of the four control-fingers 72 of the control-plate 46, 20 under conditions as will hereinafter appear.

The operation of the structure of Figs. 1 to 13, inclusive.

Let it be assumed for purposes of description, 25 that the self-opening die-head has its parts in the positions in which they are shown in Figs. 1 to 11 inclusive, in which the chasers 25 are in position to start the threading of a work-piece, indicated by the dot-and-dash lines at the left of Fig. 3.

Shortly after the teeth at the inner ends of the chasers 25 engage with and start to thread the periphery of the said work-piece, the forward end of the abutment-member 59 within the die-head structure will engage with the end of the said work-piece. Under present conditions, either the die-head structure, the work-piece, or both, may be moved in an axial direction with respect to the other, and either the die-head, the work-piece, or both thereof may be rotated with respect to each other. It is the more usual practice to rotate the die-head structure with respect to the work-piece.

After the forward end of the abutment-member 45 59 engages with the work-piece, its forward movement will thereby be halted relative to the work-piece, as will also the forward movement of the actuating-slide 56 and the actuating-bar 63. The remaining parts of the die-head structure will continue to move forwardly relative to the work-piece against the tension of the spring 65, so that relative movement will take place in an axial direction between the actuating-bar 63 and the surfaces of the helically-inclined actuating-slots 67-67. In effect, the actuating-bar 63 will move rearwardly in the said actuating-slots 67 and this movement will cause the said actuating-sleeve to turn in the direction indicated by the arrow in Fig. 11.

60 The above described turning movement of the control-sleeve 36 will turn its inclined control-surfaces 74 relative to the similarly-inclined control-surfaces 73 of the control-plate 46 and the resultant camming action will move the said control-plate forwardly relative to the body-member 20. The described forward movement of the control-plate 46 will (since the parts 46 and 33 are rigidly secured together) cause the chaser-operating sleeve 33 to move forwardly relative to both the body-member 20 and the chasers 25 carried thereby. This forward movement of the chaser-operating sleeve 33 will cause its cam-surfaces 32 to move relatively forwardly on the cam-surfaces 31 of the respective chasers 25 to thereby progressively move the latter radially,

inwardly. The described inward movement of the chasers will be progressive and at a rate which is predetermined and in accord with the desired taper of the threads to be produced upon the work-piece indicated in Fig. 3.

At the completion of the desired threading operation, the described turning movement of the control-sleeve 36 will have brought the parts into the relative positions in which they are indicated in Fig. 13. A minute further turning movement of the control-sleeve 36 will bring its clearance-notches 75 respectively fully into registry with the control-fingers 73, whereupon the spring-pressed plungers 48-48 (Figs. 5 and 6) will snap the control-plate 46, together with the chaser-operating sleeve 33, rearwardly until the rear end of the said chaser-operating sleeve strikes the stop-member 55. The relative positions now assumed by the parts 36, 46 and 63 are shown in Fig. 12.

The described rearward movement of the chaser-operating sleeve 33 will retire its cam-surfaces 32-32 rearwardly relative to the cam-surfaces 31 on the chasers 25, thereby permitting the said chasers to move radially outwardly under the urge of their respective spring-pressed plungers 28. The described movement of the chasers 25 will clear the thread-cutting teeth thereof from engagement with the work, whereupon the now-threaded work-piece and the die-head may be axially separated.

As above described, the relative rearward movement of the actuating-bar 63 and the consequent turning of the control-sleeve 36 to provide the progressively-reducing taper thread is accomplished by the engagement of the stop-member 59 with the work-piece. The same result could be achieved by any instrumentality such as a yoke (not shown, but well known in the art) riding in the annular groove 42 in the outer periphery of the actuating-sleeve 39. This will be clearly apparent when it is observed by reference to Fig. 3 in particular, that any relative rearward movement of the actuating-sleeve 39 relative to the remainder of the structure would cause the forward wall of its clearance-grooves 69 to force the actuating-bar 63 relatively rearwardly in the same manner as such action was accomplished by the relative rearward movement of the abutment-member 59 and the actuating-slide 56 to which it is attached.

After the chasers 25 have been moved into their completely retired positions, as previously described, following the completion of the threading operation, the said chasers will require resetting to restore them into substantially the positions in which they are shown in Fig. 3, in order to start another thread-cutting operation.

To effect the resetting of the die-head, the chaser-operating sleeve 33 may be moved forwardly relative to the body-member 20 and its chasers 25 and this may be accomplished by an external instrumentality riding in the annular groove 42 in the actuating-sleeve 39. Thus, if the actuating-sleeve 39 is moved forwardly relative to the body-member 20, it will, in turn, force the chaser-operating sleeve 33 forwardly.

As soon, in the forward travel of the chaser-operating sleeve 33 and its attached control-plate 46, as the respective rear faces of the control-fingers 72 are brought into registry with the high points of the control-surfaces 74 on the control-sleeve 36, the said control-sleeve will be free to turn in a direction opposite to the direction indicated by the arrow in Fig. 11. This rotary move-

ment of the control-sleeve 36 will be under the urge applied by the spring 65 acting through the actuating-bar 63 and the actuating-slots 67.

The parts will now have reassumed the positions in which they are shown in Figs. 1 to 11 inclusive, preparatory to the start of another threading operation.

The structure of Fig. 14

10 In Fig. 14 is illustrated a slightly modified form of control-plate and control-sleeve respectively similar to the control-plate 46 and the control-sleeve 36 before described, and bearing similar reference characters with respect to their various features, plus the reference character *a*.

The control-plate 46a illustrated in Fig. 14 has four inwardly-projecting control-fingers 72a, each of which has its rear face providing a control-surface 73a. Instead of being inclined as are the control-surfaces 73, the control-surfaces 73a extend in a plane at a right angle to the central longitudinal axis of the structure.

The structure of Fig. 14 also includes a control-sleeve 36a similar to the control-sleeve 36, save that its control-surfaces 74a extend in a plane at a right angle to the longitudinal axis of the structure to complement the control-surfaces 73a of the control-plate 46a.

Now, when the control-sleeve 36a is turned with respect to the control-plate 46a, in a manner similar to that described in connection with the structure of Figs. 1 to 13 inclusive, the control-plate 46a and parts connected thereto will not be moved forwardly, so that instead of cutting a thread which progressively decreases in diameter as the threading operation proceeds, a series of threads of uniform diameter will be produced.

The structure of Fig. 15

45 In Fig. 15 is illustrated another slightly modified form of control-plate and control-sleeve respectively similar to the control-plate 46 and the control-sleeve 36 before described, and bearing similar reference characters with respect to their various features plus the reference character *b*.

The control-plate 46b illustrated in Fig. 15 is provided with four inwardly-projecting control-fingers 72b, each of which has its rear face providing a control-surface 73b. Instead of being inclined in the direction of the control-surfaces 73 before referred to, the control-surfaces 73b slope in an opposite direction.

55 The structure of Fig. 15 also includes a control-sleeve 36b similar to the control-sleeve 36 save that its control-surfaces 74b slope in a direction opposite to the slope of the control-surfaces 74 before described. The control-surfaces 73a and the control-surfaces 74a substantially coincide in their respective inclinations.

When the control-sleeve 36b is turned with respect to the control-plate 46b in a manner similar to that described in connection with the structure of Figs. 1 to 13 inclusive, the control-plate 46b and the parts connected thereto will move rearwardly so that instead of cutting either a straight thread or a thread which progressively decreases in diameter as the threading operation proceeds, there will be cut a series of threads which progressively increase in diameter.

The invention may be carried out in other specific ways than those herein set forth without departing from the spirit and essential characteristics of the invention, and the present em-

bodiments are, therefore, to be considered in all respects as illustrative and not restrictive, and all changes coming within the meaning and equivalency range of the appended claims are intended to be embraced therein.

I claim:

1. A self-opening die-head having a forward chaser-carrying portion and including in combination: a body-unit comprising a body-member, a chaser-operating sleeve carried by and reciprocating in a substantially-axial direction with respect to the said body-member, and limiting-means interconnecting the said body-unit and chaser-operating sleeve and limiting the relative movement therebetween to a reciprocating movement in substantially an axial direction, the said body-unit being provided with a substantially-longitudinal slot and the said chaser-operating sleeve being provided with a plurality of laterally projecting control-fingers; a plurality of chasers carried by the forward portion of the said body-member with capacity for movement toward and away from the longitudinal axis thereof, the said chasers being operatively connected with the said chaser-operating sleeve for being moved thereby toward the longitudinal axis of the die-head structure on axial movement of said chaser-operating sleeve in a certain direction; a control-sleeve carried by the said body-unit for movement axially therewith but having capacity for oscillating movement in a circumferential direction with respect thereto and provided with a substantially-longitudinal slot inclined with respect to the slot of the said body-unit, the said control-sleeve also having its forward end formed into a plurality of circumferentially-spaced cam-surfaces engageable by the control-fingers of the said chaser-operating sleeve, said forward end of said control-sleeve being further provided with a plurality of forwardly-opening clearance-notches adjacent its said cam-surfaces, respectively; and an actuating-member extending into the respective slots of both the said body-unit and the said control-sleeve and constructed and arranged to coact with the walls of the two said slots to force the said control-sleeve to turn in a circumferential direction relative to the body-unit when the said actuating-member is moved in the direction substantially lengthwise of the die-head structure to thereby cause the plurality of cam-surfaces of the control-sleeve to slide in a generally-circumferential direction and cooperate with the control-fingers of the chaser-operating-sleeve in axially moving the latter sleeve in said certain direction, said chaser-operating sleeve being normally yieldingly urged axially in the opposite direction so that the same will, when its control-fingers align with and are urged into said clearance-notches in said control-sleeve, move in the latter direction and thereby permit quick movement of said chasers away from the longitudinal axis of said body-member.

2. A self-opening die-head having a forward chaser-carrying portion and including in combination: a body-unit comprising a body-member, a chaser-operating sleeve carried by and reciprocating in a substantially-axial direction with respect to the body-member, and limiting-means interconnecting the said body-unit and chaser-operating sleeve and limiting the relative movement therebetween to a reciprocating movement in substantially an axial direction, the said body-unit being provided with a substantially-longitudinal slot and the said chaser-operating

sleeve being provided with a plurality of inwardly-extending control-fingers; a plurality of chasers carried by the forward portion of the said body-member with capacity for movement toward and away from the longitudinal axis thereof, the said chasers being operatively connected with the said chaser-operating sleeve for being moved thereby toward the longitudinal axis of the die-head structure on axial movement of said chaser-operating sleeve in a certain direction; a control-sleeve located intermediate the said body-member and the said chaser-operating sleeve and axially movable with said body-member but having capacity for oscillating movement in a circumferential direction with respect thereto and provided with a substantially-longitudinal slot inclined with respect to the slot of the said body-unit, the said control-sleeve also having its forward end formed into a plurality of circumferentially-spaced cam-surfaces engageable by the control-fingers of the said chaser-operating sleeve, the forward end of said control-sleeve being further provided with a plurality of forwardly-opening clearance-notches adjacent its said cam-surfaces, respectively; and an actuating-member extending into the respective slots of both the said body-unit and the said control-sleeve and constructed and arranged to coact with the walls of the two said slots to force the said control-sleeve to turn in a circumferential direction relative to the body-unit when the said actuating-member is moved in the direction substantially lengthwise of the die-head structure to thereby cause the plurality of cam-surfaces of the control-sleeve to slide in a generally-circumferential direction and cooperate with the control-fingers of the chaser-operating sleeve in axially moving the latter sleeve in said certain direction, said chaser-operating sleeve being normally yieldingly urged axially in the opposite direction so that the same will, when its control-fingers align with and are urged into said clearance-notches in said control-sleeve, move in the latter direction and thereby permit quick movement of said chasers away from the longitudinal axis of said body-member.

3. A self-opening die-head having a forward chaser-carrying portion and including in combination: a body-member provided with two substantially-longitudinal slots each diametrically opposite the other; a plurality of chasers carried by the forward portion of the said body-member with capacity for movement toward and away from the longitudinal axis thereof; a chaser-operating sleeve surrounding and reciprocating in a substantially-axial direction with respect to the said body-member and operatively connected with the said chasers to move the same inwardly toward the axis of the die-head structure on axial movement of said chaser-operating sleeve in a certain direction, the said chaser-operating sleeve being provided with a plurality of control-fingers and with two slots diametrically opposite each other in both registry and parallelism with the slots in the said body-member; limiting-means interconnecting the said body-member and chaser-operating sleeve and limiting the relative movement therebetween to a reciprocating movement in substantially an axial direction; a control-sleeve axially slidably interfitted between said body-member and chaser-operating sleeve and axially movable with said body-member but having capacity for oscillating movement in a circumferential direction with respect thereto and provided with a substantially-longitudinal slot inclined with respect to the slot of the said body-unit, the said control-sleeve also having its forward end formed into a plurality of circumferentially-spaced cam-surfaces engageable by the control-fingers of the said chaser-operating sleeve, the forward end of said control-sleeve being further provided with a plurality of forwardly-opening clearance-notches adjacent its said cam-surfaces, respectively; and an actuating-member extending into the respective slots of both the said body-unit and the said control-sleeve and constructed and arranged to coact with the walls of the two said slots to force the said control-sleeve to turn in a circumferential direction relative to the body-unit when the said actuating-member is moved in the direction substantially lengthwise of the die-head structure to thereby cause the plurality of cam-surfaces of the control-sleeve to slide in a generally-circumferential direction and cooperate with the control-fingers of the chaser-operating sleeve in axially moving the latter sleeve in said certain direction, said chaser-operating sleeve being normally yieldingly urged axially in the opposite direction so that the same will, when its control-fingers align with and are urged into said clearance-notches in said control-sleeve, move in the latter direction and thereby permit quick movement of said chasers away from the longitudinal axis of said body-member.

to and being provided with two substantially-longitudinal slots each diametrically opposite the other and in registration respectively with the slots in the said body-member and chaser-operating sleeve and both inclined with respect to the slots of the said body-member and chaser-operating sleeve, the said control-sleeve also having its forward end formed into a plurality of circumferentially-spaced cam-surfaces engageable by the control-fingers of the said chaser-operating sleeve, the forward end of said control-sleeve being further provided with a plurality of forwardly-opening clearance-notches adjacent its said control-surfaces, respectively; and an actuating-member extending in a substantially-diametric direction into the respective pairs of slots said body-member and said chaser-operating and control-sleeves and constructed and arranged to coat with the walls of said pairs of slots to force the said control-sleeve to turn in a circumferential direction relative to the body-member when the said actuating-member is moved in a direction substantially lengthwise of the die-head structure to thereby cause the plurality of cam-surfaces of the said control-sleeve to slide in a generally-circumferential direction and cooperate with the control-fingers of the chaser-operating sleeve in axially moving the latter sleeve in said certain direction, said chaser-operating sleeve being normally yieldingly urged axially in the opposite direction so that the same will, when its control-fingers align with and are urged into said clearance-notches in said control-sleeve, move in the latter direction and thereby permit quick movement of said chasers away from the longitudinal axis of said body-member.

4. A self-opening die-head having a forward chaser-carrying portion and including in combination: a body-member provided with two substantially-longitudinal slots each diametrically opposite the other and with an axial chamber intersected by the said slots; a plurality of chasers carried by the forward portion of the said body-member with capacity for movement toward and away from the longitudinal axis thereof; a chaser-operating sleeve carried by and reciprocating in a substantially-axial direction with respect to the said body-member and operatively connected with the said chasers to move the same inwardly toward the axis of the die-head structure on axial movement of said chaser-operating sleeve in a certain direction, the said chaser-operating sleeve being provided with a plurality of control-fingers and with two slots diametrically opposite each other in both registry and parallelism with the slots in the said body-member; a control-sleeve carried by the said body-member interiorly of the said chaser-operating sleeve and being axially movable with said body-member but having capacity for oscillating movement in a circumferential direction with respect thereto and provided with two substantially-longitudinal slots each diametrically opposite the other and in registration respectively with the slots in the said body-member and chaser-operating sleeve and both inclined with respect to the slots of the said body-member and chaser-operating sleeve, the said control-sleeve having its forward end formed into a plurality of circumferentially-spaced cam-surfaces engageable by the control-fingers, respectively, of the said chaser-operating sleeve, said forward end of said control-sleeve being further provided with a plurality of forwardly-opening clearance-notches adjacent its said cam-surfaces,

respectively; an actuating-member extending in a substantially-diametric direction into the respective pairs of slots of the said body-member, the said chaser-operating sleeve and the said control-sleeve and constructed and arranged to coat with the walls of the said pairs of slots to force the said control-sleeve to turn in a circumferential direction relative to the body-member when the said actuating-member is moved in a direction substantially lengthwise of the die-head structure to thereby cause the plurality of cam-surfaces of the said control-sleeve to slide in a generally-circumferential direction and cooperate with the control-fingers of the chaser-operating sleeve in axially moving the latter sleeve in said certain direction, said chaser-operating sleeve being normally yieldingly urged axially in the opposite direction so that the same will, when its control-fingers align with and are urged into said clearance-notches in said control-sleeve, move in the latter direction and thereby permit quick movement of said chasers away from the longitudinal axis of said body-member; and a reciprocating actuating-slide movable in the axial chamber in the said body-member and operatively connected to the said actuating-member to move the same.

5. A self-opening die-head having a forward chaser-carrying portion and including in combination: a body-member provided with two substantially-longitudinal slots each diametrically opposite the other; a plurality of chasers carried by the forward portion of the said body-member with capacity for movement toward and away from the longitudinal axis thereof; a chaser-operating sleeve carried by and reciprocating in a substantially-axial direction with respect to the said body-member and operatively connected with the said chasers to move the same inwardly toward the axis of the die-head structure on axial movement of said chaser-operating sleeve in a certain direction, the said chaser-operating sleeve being provided with a plurality of control-fingers and with two slots diametrically opposite each other in both registry and parallelism with the slots in the said body-member; a control-sleeve carried by the said body-member interiorly of the said chaser-operating sleeve and being axially movable with said body-member but having capacity for oscillating movement in a circumferential direction with respect thereto and provided with two substantially-longitudinal slots each diametrically opposite the other and in registration respectively with the slots in the said body-member and chaser-operating sleeve and both inclined with respect to the slots of the said body-member and chaser-operating sleeve, the said control-sleeve having its forward end formed into a plurality of circumferentially-spaced cam-surfaces engageable by the control-fingers, respectively, of the said chaser-operating sleeve, the forward end of said control-sleeve being further provided with a plurality of forwardly-opening clearance-notches adjacent its said control-surfaces, respectively; an actuating-bar extending in a substantially-diametric direction into the respective pairs of slots of the said body-member, chaser-operating sleeve and the said control-sleeve and constructed and arranged to coat with the walls of the said pairs of slots to force the said control-sleeve to turn in a circumferential direction relative to the body-member when the said actuating-bar is moved in a direction substantially lengthwise of the die-head structure to thereby cause the plurality of cam-surfaces of the said control-sleeve to slide in a

generally-circumferential direction and cooperate with the control-fingers of the chaser-operating sleeve in axially moving the latter sleeve in said certain direction, said chaser-operating sleeve being normally yieldingly urged axially in the opposite direction so that the same will, when its control-fingers align with and are urged into said clearance-notches in said control-sleeve, move in the latter direction and thereby permit quick movement of said chasers away from the longitudinal axis of said body-member; and a reciprocating actuating-sleeve mounted for axial movement upon the exterior of the said chaser-operating sleeve and engaging therewith for moving the latter in said certain direction, said actuating-sleeve covering said actuating-bar and said pairs of slots of said body-member and of said chaser-operating and control-sleeves.

6. A self-opening die-head for conical work, including in combination: an abutment-member extending axially of the die-head and having a work-abutting end and a laterally-extending bar spaced from said end; axially slidably-interfitted chaser, control and operating sleeves, respectively, of which said chaser sleeve is innermost and axially slidable on said abutment-member and said chaser and operating sleeves and abutment-member are connected for independent axial but nonrotational movement relative to each other, and said control-sleeve is connected with said chaser-sleeve for non-axial but free rotational relative movement between them, and has a slot inclined to its axis and receiving said bar for turning said control-sleeve in opposite directions relative to said operating-sleeve on relative axial movement between said abutment-member and chaser-sleeve in opposite directions;

5 a chaser carried by said chaser-sleeve for movement inwardly toward and outwardly from the axis of the latter; means including cams on said operating and chaser sleeves, respectively, cooperating to move said chaser inwardly and outwardly on axial movement of said operating-sleeve in opposite directions, respectively, relative to said chaser; and means including a cam-face at one end of said control-sleeve and a laterally-projecting cam-lug on said operating-sleeve cooperating with said cam-face to cause on relative rotation between the latter sleeves in said opposite directions relative axial movement between said operating and control-sleeves in opposite directions, respectively, said operating-sleeve being with its cam-lug normally yieldingly urged against said one end of said control-sleeve and the latter having in said one end and adjacent said cam-face an axially-extending notch into which jumps said cam-lug on clearing said cam-face, thereby permitting axial movement of said operating-sleeve in one of said opposite directions in which to permit quick outward movement of said chaser from operative engagement with the work.
